CLAIM

The ornamental design for a pickle ball, as shown and described.

DESCRIPTION

FIG. 1 is a perspective view of a pickle ball of my new design from the front, top;

FIG. 2 is an elevational view thereof from the front;

FIG. 3 is an elevational view thereof from the rear;

FIG. 4 is an elevational view thereof from the left;

FIG. 5 is an elevational view thereof from the right;

FIG. 6 is a top plan view thereof; and,

FIG. 7 is a bottom plan view thereof.

The broken lines in the figures depict portions of the pickle ball that form no part of the claimed design.

1 Claim, 7 Drawing Sheets
